[57] **CLAIM**

The ornamental design for a combined push broom head and scraper, as shown and described.

DESCRIPTION

FIG. 1 is a side elevational view of a combined push broom head and scraper showing my new design, the opposite side being a mirror image;

FIG. 2 is a top plan view thereof;

FIG. 3 is a rear elevational view thereof;

FIG. 4 is a front elevational view thereof;

FIG. 5 is a bottom plan view thereof;

FIG. 6 is a sectional view thereof, taken along line 6—6 of FIG. 3; and

FIG. 7 is an enlarged perspective view thereof.

The broken lines showing of a handle and/or bristles in FIGS. 1-7 are for illustrative purposes only and form no part of the claimed design.
